HAT IRONING MACHINE OR THE LIKE

James F. Doran, deceased, late of Danbury, Conn.,
by John C. Doran, executor, Danbury, Conn.

Application January 9, 1932. Serial No. 585,776

36 Claims. (Cl. 223—28)

This invention relates to an apparatus for ironing and luring hats, such as felt hats.

One of the objects of this invention is to provide an apparatus of the above-mentioned character which will be simple, practical, and thoroughly durable. Another object is to provide an apparatus of the above character which will be efficient and reliable in operation. Another object is to provide an apparatus of the above character which will be of ready and inexpensive manufacture. Another object is to provide an apparatus of the above character in which the hat operating tool may traverse dependably a comparatively large surface of the hat in a short period of time. Another object is to provide an apparatus of the above character in which the speed of drive may be materially increased in order to change the character of operation without harm to the parts or damage to the hat. Another object is to provide an apparatus of the above character which is of wide application and easily adaptable to many varied conditions of use. Another object of this invention is to provide an apparatus of the above character in which the hat operating tool is brought into contact with all portions of the surface of the hat crown while exerting a substantially even pressure even though the hat crown may be oval. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of this invention.

Figure 1 is a side elevation of the machine ready for operation;

Figure 2 is a side elevation, on an enlarged scale, of certain parts of the machine, certain of the parts thereof being shown in section;

Figure 3 is a vertical longitudinal sectional view, on an enlarged scale, of a portion of the machine, more particularly of part of the driving mechanism that is seen in elevation at the left hand end of Figure 2;

Figure 4 is a vertical sectional view taken along the line 4—4 of Figure 3;

Figure 5 is a vertical sectional view taken along the line 5—5 of Figure 3;

Figure 6 is a horizontal sectional view as seen along the line 6—6 of Figure 2;

Figure 7 is a vertical sectional view taken along the line 7—7 of Figure 3;

Figure 8 is a perspective view of one of the parts of the machine;

Figure 9 is a perspective view of another part 60 of the machine;

Figure 10 is an elevation of certain parts of the machine, substantially as seen along the line 10—10 of Figure 2, these parts being shown on the right hand side of Figure 2;

Figure 11 is a vertical sectional view of the parts shown in Figure 10 and taken along the line 11—11 of Figure 2;

Figure 12 is a horizontal sectional view taken along the line 12—12 of Figure 10;

Figure 13 is a vertical sectional view, on an enlarged scale, taken along the line 13—13 of Figure 11;

Figure 14 is a diagrammatic showing of the apparatus when operating on an oval shaped hat, 75 and

Figure 15 is a similar diagrammatic view of the apparatus operating on a hat of circular cross-section.

Similar reference characters refer to similar parts throughout the several views of the drawings.

As conducive to a clearer understanding of certain of the features of this invention, it might here be pointed out that in ironing machines, luring machines, and the like, considerable difficulty has been experienced in attempting to dependably apply the ironing tool to a rotating hat body at a substantially constant pressure regardless of the position of the tool as it traverses the body of a rotating hat. Inasmuch as this tool must assume a plurality of positions about the crown or body of the rotating hat, these positions being in different vertical planes and at various angles and varying with the cross-section of the hat, the problem of applying an even pressure of the tool against the hat at all times during this operation has constantly presented manifold difficulties. In order that the hat may be ironed and lured to perfection, it is highly desirable and most advantageous

to achieve such a constant pressure at all times during the ironing or luring operation. Furthermore, it has been found that in ironing or luring hats having crowns of different shapes, the problems mentioned above are accentuated. For example, when a hat body having a substantially circular crown is being ironed, the operation may

take place at a comparatively rapid speed due to the relatively simple movements of the tool as it moves about the rotating hat body. However,

70

75

80

85

90

95

100

105

110

if, for example, a hat body having an oval-shaped crown is being ironed or lured, with the body rotating about the center of the oval, the tool must move toward and away from the axis of rotation several times during each rotation of the hat body, resulting not only in repeated variations in the pressure on the hat but also in great irregularity of action unless the speed of rotation is sufficiently reduced to permit the iron to readjust itself to the various positions it must assume nearer to or farther away from the axis of the hat. A speed of rotation of the hat body that is appropriate for ironing a round or circular cross-sectional hat is inappropriate for ironing a hat body of oval cross-section and vice versa. One of the various objects of this invention is to provide a hat ironing machine which, while operating successfully and efficiently, overcomes the above-mentioned difficulties, irrespective of the cross-section of the hat, as well as many others in a practical, efficient and economical manner.

Referring now to Figure 1 in detail, there is shown a standard 10, which may be of any suitable construction, having mounted thereupon a frame 11. Frame 11 may be secured to standard 10 in any reliable manner as, for example, by bolts generally indicated at 12, and is adapted to carry the moving parts of my machine in a manner to be described more fully hereinafter. Extending along the top of frame 11 is a bore 13 (Figure 2) running substantially parallel to the top of standard 10, while rotatably mounted within bore 13 is a shaft 14 driven in a manner to be described hereinafter.

Shaft 14 extends from the right hand side of frame 11, as viewed in Figure 2, and upon this end of the shaft a hat block 15 may be detachably mounted. Rigidly mounted upon this end of shaft 14 is a sleeve 16 (Figure 2) and pivotally connected thereto and in suitable slots therein is a series of fingers, preferably three in number, and generally indicated at 17, a specific example of which is finger 18, all of these fingers being similar in construction. Finger 18 is pivoted to sleeve 16 at 19 and extends in a right hand direction, as viewed in Figure 2, into an annular recess 20 within hat block 15 when the block is related to the shaft. The top surface of finger 18 curves upwardly to form a cam surface or the like, and seated between finger 18 and sleeve 16 is a spring 21 acting to force the finger away from the sleeve or block. Block 15 has a central or axial recess 15a into which is received a pin 16a carried by sleeve 16 and extending coaxially with the shaft 14. When the block is related to the right hand end of shaft 14, as viewed in Figure 2, fingers 18 hold the block in this position if pressure is exerted upon the fingers against the action of the springs 21.

Slidably mounted upon sleeve 16 and about fingers 18 is a collar 22 (Figure 2), the right hand end of which has a cam surface 23 upon its inner side. Accordingly, if collar 22 is forced in a right hand direction along fingers 17, cam surface 23, coacting with the cam surface upon the fingers, forces the fingers inwardly or against the hub 24 of block 15. To force collar 22 in this direction, there is provided in the latter an annular recess or groove 25 within which rests a ring 26. Pivotally connected to ring 26, preferably at points spaced 180° about the latter, are two links 27 (one on each side of the apparatus and only one being shown in Figures 1 and 2) which are in turn pivotally connected to the lower forked end 28 of a lever 28 as at points 29. Lever 28 is pivotally

mounted upon frame 11 in any convenient manner as at 28a and at a point spaced from pivotal connection 29.

Accordingly, one may actuate collar 22 in either direction by moving lever 28 and, if lever 28 is moved in a left hand direction, as view in Figure 2, collar 22 is moved in a right hand direction to force fingers 17 against hub 24 of block 15 and thus hold the block in its operative position upon pin 16a. On the other hand, if lever 28 is moved in a right hand direction to move collar 22 toward the left, springs 21 act against fingers 18 to force the fingers out of engagement with the hub so that it may be released.

In order to hold the lever 28 in its effective position, as described above, there is provided a spring 30 connected to the lever and to stationary part 211 secured to frame 11. Inasmuch as spring 30 is of the tension type, thus acting to pull lever 28 in a left hand direction, as viewed in Figure 2, the hat block 15 is continuously held in position upon pin 16a unless the operator wishes to release it by moving lever 28 in a right hand direction against the tension of the spring.

Rigidly secured to lever 28 at its pivotal point 28a is an arm 32 and pivotally connected to arm 32 is a rod 33 extending downwardly, as more clearly shown in Figure 1. Pivotally connected to standard 10, at any convenient point as at 10a, is a foot treadle or lever 34 having rod 33 suitably connected thereto. Accordingly, pressure exerted upon foot lever 34 forces lever 28 in a right hand direction, as viewed in Figures 1 and 2, against the action of spring 30 to release block 15 in the manner described above and, subsequent removal of this pressure, allows spring 30 to pull back lever 28 and move fingers 17 into their gripping position, as has been described above. In this manner a hat block, such as block 15, carrying a hat 35, may be secured to 115 and held coaxially with shaft 14 in a reliable manner.

Referring now to Figures 1 and 2, there is a casing, generally indicated at 31, mounted upon the left hand side of frame 11, as viewed in Figure 1, and carrying a transmission or drive for shaft 14 adapted to coact with certain other parts of the apparatus in a manner to be described in detail hereinafter. As is more clearly shown in Figure 8, it is preferred to form casing 31 as a single piece which may be suitably cast of iron or any other desirable metal. Formed upon the left end of casing 31 is a flange 38 extending inwardly from the periphery of the casing (Figures 2 and 3). Suitable threaded holes 40 extending through flange 38 are disposed at intervals thereabout and, as shown in Figure 8, casing 31 tapers from a point near the end bearing flange 38 to its opposite end 41 which will hereinafter be termed the "forward" end. The inner diameter of end 41, formed by a flange 41a (Figure 3), is such that flange 41a fits into a bezel or recess 42 (Figures 2 and 3) formed upon frame 11 and concentric with the bore 13 in which shaft 14 rotates.

Turning to Figures 2 and 3, a bracket-like portion 43 of casing 31 extends downwardly substantially parallel to the left hand side or end of frame 11. The downwardly extending arm 43 is preferably cast integrally with the casing 31 and rigidity and great strength are provided by the integrally cast wings or ribs 43a and 43b (Figures 2 and 3) and ribs 43c and 43d (Figure 7) extending at right angles to each other. Thus

80

part 43 has great resistance to any tendency to bend or warp.

Immediately to the right of the lower end of arm 43 (see Figure 2), the frame 11 is bored out and threaded to receive a short and relatively heavy stud 45, preferably of steel and of great rigidity. The stud 45 is shouldered so that it may be tightly threaded into place with the shoulder 45a and brought up against the face of frame 11, 10 thus not only securely anchoring the stud but also adding to its resistance to any tendency to bend. The left hand end of stud 45 is threaded and, as the casing 31 is fitted onto frame 11 by fitting flange 41a (Figure 3) into the bezel 42, 15 the lower end of bracket 43, being suitably apertured, is received onto the stud 45 where it is tightly clamped in place by nuts 44 and 46 which are threaded onto stud 45.

Stud 45 acts as a cantilever for supporting casing 31 (see Figure 1) in its allotted position upon frame 11 and stud 45, due to its cantilever action, supports casing 31 in proper association with frame 11 in an efficient manner. When casing 31 is so positioned with stud 45 in place, this 20 cantilever action prevents displacement thereof in any direction. Accordingly, by utilizing a single means for securing casing 31 to frame 11, nevertheless, it is found to be amply sufficient and a thoroughly reliable means for maintaining 25 the casing in its operative position and for achieving certain other important coactions.

However, as is more clearly shown in Figure 7, it is also preferred to provide a suitable number of set screws (Figure 7), such as screws 47 30 and 48, extending through suitable threaded openings 49 (Figure 8) and 50 in flange 41a (Figure 3). Set screws 47 and 48 extend into substantially countersunk recesses 51 and 52 (Figure 7) upon the surface of recess 42. Accordingly, 35 set screws 47 and 48 act as an additional securing agent to prevent any endwise displacement of casing 31 from frame 11. Screws 47 and 48 coact with stud 45 to hold the casing in its proper position, but should these screws become loosened, 40 stud 45, due to its cantilever action, as described above, still continues to support casing 31. By securing casing 31 to frame 11 in this simple and thoroughly practical manner, one insures an efficient operation of the mechanism carried 45 thereby and of the machine without hazarding a breakdown which might ensue should the casing become dislodged from the frame.

Extending from the left of casing 31, as is best shown in Figures 7 and 8, is a dished flange 53, the axis of which is substantially at right angles to the axis of flange 38. Flange 53 is integrally cast with casing 31 and also with the reinforcing rib 43d (Figure 7) and thus the rigidity of depending arm 43 is further increased 60 and the rigid support of stud 45 is thus directly transmitted to flange 53 and the parts it carries. The extreme edge of dished flange 53 is bezeled as at 54 (Figure 7) and fitted thereover is the end of the frame or casing 55 of an electric 65 motor generally indicated at 56. The latter may be of standard construction and preferably is. Extending from the frame 55 of motor 56 is a series of stud bolts generally indicated in Figure 7 at 58 and, as more clearly shown in Figure 8, 70 bolts 58 extend through holes 59 in the flange 53, thereafter to receive nuts 61 (Figures 3 and 7) threaded thereon. Flange 53 is formed or cast as at 60 (Figure 8) to provide space for the nuts 61 to be brought up tightly and thus to draw and 75 hold motor 56 flush against flange 53 in the

position shown in Figure 7. Flange 53, moreover, is provided with notches or recesses 53a about its periphery, illustratively four in number and three of which are better shown in Figure 8, while two of which clearly appear in Figure 7, and into these recesses 53a are received or fitted lugs or projections 58a of the frame or casing 55 of the motor 56, thus assuring a nice interfitting or interengagement of motor, frame and flange 53.

Motor 56 is preferably of the universal type adapted to operate on either direct or alternating current according to the particular needs of the user of the machine. Furthermore, as motor 56 is securely attached to casing 31, it is reliably secured to the machine against any possible displacement. The tendency for the weight of the motor 56 to swing the casing 31 in counter-clockwise direction, as viewed in Figure 7, is reliably resisted by the cantilever stud 45, the latter 80 together with the interfitting parts 41a and 42 (Figures 2 and 3) insuring a dependable transmission of the weight of all these parts to the main frame 11.

This mounting of the casing 31 and its related 85 parts is important and achieves many great advantages; certain of the coactions of the mounting of this casing 31 with certain other features of the invention such as the control of the drive of the machine from motor 56, will be described 90 more fully hereinafter.

Turning now to Figure 3, an end plate 62 fits over opening 39 (Figure 8) in casing 31, the outer portion thereof being in registry with flange 38. Suitable cap screws 63 extend through end plate 62 and are threaded into holes 40 in flange 38 to secure the end plate in this position. Formed substantially at the center of end plate 62 is flanged opening 64 having its surface bezeled as at 65 to receive the outer race of an anti-friction radial and thrust bearing 66. Bearing 66 may be of any suitable character, although it is preferred to use a ball bearing in this instance. Upon leaving bore 13, a reduced end portion 67 of shaft 14 extends through casing 100 31; the left hand end of end portion 67 is reduced as at 139 to receive the inner race 141 of the bearing 66. A nut 140 is threaded upon end 139 of shaft 14 and clamps in place the race 141 of bearing 66 so that race 141 rotates with shaft 110 14. Closing over the end 139 of the shaft is a cup-shaped member 142 lying flush against end plate 62 and secured thereto preferably by screws 143; thus casing 31 is dependably closed.

Fitting rotatably about portion 67 of shaft 14 115 is a bearing bushing 144 (Figure 3) of any suitable metal as, for example, bronze. Rigidly mounted upon bearing bushing 144 is a sleeve 145 and secured thereto at its right hand end is a worm wheel 146. Worm wheel 146 is connected to sleeve 145 by way of a set screw 147 threaded through the hub of worm wheel 146 and received into a recess in the sleeve. Also, it is preferred to key the worm wheel 146 and sleeve 145 together as by the key 148. Thus worm 140 wheel 146 and sleeve 145 are reliably secured together against any possible relative movement.

Meshing with worm wheel 146 is a worm 149 which in turn is secured, as by key 157, to a shaft 150, as is more clearly shown in Figure 7. Casing 31 is bored out coaxially as at 151 and 152 (Figure 7) to receive the outer races 162 and 153 respectively of two ball bearings, the inner races 161 and 154 of which are fitted upon shaft 150. Inner race 154 rests against an enlarged part 150

155 of shaft 150 and a sleeve 156 is interposed between race 154 and the left end of worm 149. Against the right hand end of worm 149 abuts a sleeve 159 upon a bezel of which inner race 161 is mounted preferably projecting beyond the sleeve 159. The right hand end of shaft 150 is threaded to receive a nut 164 and a lock-nut 163.

10 A lock washer 165 may be interposed between the nut 164 and sleeve 159. The nut 164, when tightened, clamps the parts 161, 159, 149, 156 and 154 between itself and the shoulder formed by the enlarged part 155 of the shaft; thus these parts are made dependably to rotate with the shaft 150 and the latter is thus mounted. There 15 is also provided a cup-shaped member 166 (Figures 7, 4 and 1) fitted over the end of shaft 150 and secured to casing 31 by screws 167 threaded into the casing. Thus this opening in the casing 31 is also dependably closed.

20 Still referring to Figure 7, connected to armature or rotor 168 of motor 56 is the motor shaft 169 preferably resting within a suitable bearing 170 associated with frame 55 of the motor. Extending from the right hand end of shaft 169 25 (Figure 7) is a projection 171 fitted into a corresponding recess in the left hand end of shaft 150. Thus the two shafts are dependably aligned. To effect a driving connection therebetween, there is provided a transverse slot 172 in shaft 150 (see 30 Figure 4) into which cross portions 173 of shaft 169 extend, these parts being so proportioned that a snug fit is formed therebetween. In this manner shaft 169 is secured to shaft 150 in a simple and reliable manner and well adapted to 35 withstand the wear and tear of operation.

When motor 56 (Figure 7) is operating, shaft 150 is rotated by motor shaft 169, this rotation taking place free from undue binding or friction due to their alignment and due to the bearings 40 so that worm 149, while being free to rotate with the shaft, is securely held against endwise movement or movement in a direction parallel to the axis of shaft 150. As described above, worm 149 meshes with worm wheel 146 and, therefore, 45 when worm 149 is rotating, worm wheel 146 also rotates. Due to the fact that sleeve 145 is secured to worm wheel 146, this sleeve is rotated and such rotation takes place independently of any motion in either direction of shaft 14, bushing 144, preferably of bronze, rotating with the sleeve 145 and providing a good bearing surface for such 50 relative rotation.

As is more clearly shown at the left in Figure 3, substantially adjacent opening 64 in end 55 plate 62 is an inwardly extending annular flange 174, integrally formed with the plate 62, upon which is rotatably mounted one side plate or disk-like member 175 of an inner housing generally indicated at 176 (Figures 3, 4 and 5). The 60 other side plate 177 (Figure 3) of housing 176 is also disk-like and rotatably mounted upon sleeve 145, having a bearing upon the latter at 177a. Side plates 175 and 177 are connected by a pair of transverse parts 178 and 179, as more 65 clearly shown in Figure 5. Parts 178 and 179 are substantially portions of a cylindrical drum connecting the plates 175 and 177, the drum being cut away to leave the parts 178 and 179 sufficiently spaced to allow for the mounting there- 70 between of the various rotatable parts shown, for example in Figure 5, and to be described more fully hereinafter. Preferably housing 176 is an integral part and may be formed integrally into the above-described connected parts by casting 75 from any desirable metal.

As is more clearly shown in Figure 3, a pair of stud shafts 180 and 181 bridge side plates 175 and 177 of housing 176. The axes of shafts 180 and 181 are preferably diametrically opposed with respect to the axis of shaft 14, as is better shown in Figure 5. In order to rigidly secure shafts 180 and 181 against displacement and to prevent rotation thereof, taper pins 183 and 184 (Figure 3) extend preferably from the edge of side plate 175 through the shafts.

80 Rotatably disposed upon shafts 180 and 181 are bearing bushings 185 and 186 respectively (Figure 3) and fixedly mounted thereupon are respectively pinions 187 and 188 meshing with a pinion 189 (Figures 3 and 5). Pinion 189 is preferably an integral part of sleeve 145 (Figure 3).

85 Pinions 190 and 191 are also fixedly mounted upon bushings 185 and 186 respectively (Figure 3) and preferably are respectively integral with pinions 187 and 188. Accordingly, pinions 191—188 rotate about shaft 181 and pinions 190—187 rotate about shaft 180 (Figures 3 and 5). Pinions 190 and 191 mesh with a pinion 192 positioned to the left of pinion 189 at the left end 90 of sleeve 145, as viewed in Figure 3. Thus pinions 192 and 189 are disposed between side plates 175 and 177 of housing 176, while the latter will be seen to be mounted for rotation about the axis of shaft 14 with which pinions 192 and 189 95 are coaxial. Pinion 192 is rigidly mounted upon portion 67 of shaft 14 and is secured against axial displacement by a set screw 193 extending through a hub portion 194 of the pinion into the shaft, as is best shown in Figure 3, and is made 100 to rotate with shaft 14 by a key 195 fitted between pinion 192 and portion 67 of shaft 14.

105 Turning now to Figures 4 and 5, a stud shaft 196 is disposed between side plates 175 and 177 of housing 176 and pivoted thereupon is what shall 110 hereafter be termed a pawl member 197. As is more clearly shown in Figure 9, pawl member 197 is shaped to provide a part including a downwardly extending portion 198 carrying gear teeth 199 of the same pitch as the teeth of pinion 192 115 on shaft 14, and a lug or lever arm 200 extending upwardly above the axis of the pawl, as viewed in this figure. Pawl 197 is bored out as at 197a to receive shaft 196; the latter, acting as the axis about which pawl 197 pivots, is circumferentially 120 spaced from shafts 180 and 181, as is best shown in Figures 4 and 5. Furthermore, gear portion 198 (Figure 9) of pawl 197 is displaced axially 125 from the lever portion 200 and, when mounted on shaft 196, gear portion 198 is in substantial 130 alignment with pinion 192 and pinions 190 and 191 (see also Figure 2). However, lug 200 (Figures 2 and 4), due to this displacement, is brought 135 into a position where it overlaps side plate 177 of housing 176, the side plate 177 being cut away (Figure 4) for this purpose. Teeth 199 of pawl 197 are so proportioned that they may mesh with the teeth of pinion 192 (Figure 4).

140 Projecting radially outwardly from part 179 (Figure 5) of housing 176 is a lug 201 and extending between lug 201 and lug or lever arm 200 of pawl 197 is a tension spring 202. Consequently spring 202 moves pawl 197 about its axis and forces teeth 199 thereof into mesh with pinion 192. The shaft 196, upon which pawl 197 pivots, 145 is so spaced from the periphery of pinion 191 (Figures 4 and 5) that, when teeth 199 of pawl 197 mesh with pinion 192, portion 198 of the pawl swings over against the teeth of pinion 191. Accordingly, when pawl 197 is in the full-line 150

- position shown in Figure 4, clockwise rotation of housing 176 causes a like rotation of pinion 192 and hence of shaft 14, for pinion 191 (Figures 4 and 5) prevents pawl 197 from swinging about shaft 196 beyond this full-line position. On the other hand, pinion 192 may be rotated clockwise (Figures 4 and 5) relative to housing 176, spring 202 yieldingly permitting the teeth of pinion 192 to by-pass those on the pawl. 80
- 10 As is more clearly shown in Figure 4, the peripheral portions of side plate 177 are cut away in the region of pawl 197 to provide also clearance for lug 200 of pawl 197. Furthermore, side plate 175 is so shaped as to present a face or shoulder 85
- 15 203 to one side of lug 200 and, consequently, pawl 197 comes into contact therewith when pivoting about its axis against the tension of spring 202 to assume the dotted line position shown in Figure 4. 90
- 20 Referring now to the upper right hand portion of Figure 3, a plunger 204 is slidably mounted within a suitable sleeve-like extension 205 (see Figure 8) of casing 31. Plunger 204 is free to slide in either direction parallel to the axis of 95
- 25 shaft 14 and consequently toward and away from housing 176. As is more clearly shown in Figure 2, plunger 204 is connected by a link 206 to the lower end 208 of lever 209. Lever 209 is preferably pivotally mounted upon a stud shaft 210
- 30 extending from a latch member 211 secured to the top side of frame 11. Upon the upper curved face of locking member 211 are two slots 212 and 213 into which a latch rod 214 is adapted to fit; the latter is preferably slidably related to lever 35
- 35 209 and may be actuated to disengage from a slot in any suitable manner as, for example, by a knob or button 215 adapted to act against a spring 216. Thus, lever 209 may be held in one of two positions according to which of slots 212 and 213 rod 214 interfits. When lever 209 is in the position shown in Figure 2, plunger 204 is positioned within housing 205 but if the lever is moved to its right hand position, as viewed in Figure 2, plunger 204 is extended into casing 31 40
- 45 and into substantial alignment with side plate 175 and lug 200 of pawl 197. 100
- Let it be assumed that plunger 204 is withdrawn and hence is in the position shown in Figure 3 so that lever 209 is in the position shown 105
- 50 in Figure 2 and also that motor 56 is operating to rotate shaft 150 (Figure 7). Worm 149 rotates worm wheel 146 (Figure 3). Worm wheel 146, which is connected to pinion 189 by way of sleeve 145, rotates pinion 189 about shaft portion 67 (Figure 3). As is best shown in Figure 4, spring 202, when unimpeded, tends to move and hold pawl 197 in mesh with pinion 192. Consequently pinion 189, if driven in clockwise direction as viewed in Figures 4 and 5, and it is in 110
- 55 this direction that it is driven by the worm and worm wheel above mentioned, will cause pinions 188—191 (also pinions 187—190) to rotate together with the housing 176 in which these parts are mounted in a clockwise direction around pinion 192 because housing 176 is free to rotate about the axis of shaft 14 and driving pinion 189 is of a larger diameter than driven pinion 192; but this is the direction that causes the teeth 199 in 115
- 60 pawl 197 to ride into mesh with the teeth of pinion 192. Hence pawl 197 is swung in clockwise direction about its shaft 196 (Figures 4 and 5), bringing up against the pinion 191 into the full line position of Figure 4. Pinion 191 thus acts as a stop for pawl 197 and the latter prevents relative rotation of the above-mentioned 120
- 65 pinions. However, as described above, pinion 192 is secured to portion 67 of shaft 14 and therefore the pinion 189, when the above parts are in this non-rotating position as determined by the pawl 197, rotates the entire housing 176 with the pinions carried by it about the axis of shaft 14 and, through pawl 197, drives the shaft 14. Thus there is achieved a direct drive from the motor through worm 149 and worm wheel 146 at a speed determined by the gear ratio of the latter. The purpose and coaction of this driving speed with certain other features of the invention will be described more fully hereinafter. 125
- 70 When it is desired to drive shaft 14 at a greater speed (as is pointed out hereinafter), lever 209 is moved into its right hand position as viewed in Figure 2 and hence into that position in which latch rod 214 interfits with slot 212. Consequently, during the movement of lever 209 in this direction, plunger 204 (Figures 2 and 3) is moved to the left, toward the rotating inner housing 176. It first abuts against the side plate 177 until the cut-out 203 (Figure 4) in the latter, which is rotating in a clockwise direction as viewed and as indicated by the arrows in Figures 4 and 5, is brought around to plunger 204 when it slides off the face of the plate 177 and is positioned in the path of the lever arm or lug 200 of pawl 197. The motion of rotating housing 176 carries the pawl 197 toward the plunger rod 204 whereupon lever arm 200 engages the rod 204 and swings the pawl 197 out of mesh with pinion 192 and against shoulder 203 of side plate 175 so that it assumes the dotted-line position shown in Figure 4. Furthermore, plunger 204 thus stops the rotation of housing 176. With the parts in this position, all of the pinions mounted within and associated with housing 176 are free to rotate, while rotation of the housing is prevented. 130
- 75 Now the drive of shaft 14 is at a different speed. Pinion 189 is still rotated as it was previously for it is connected to worm wheel 146 by way of sleeve 145. Pinion 189 now rotates smaller pinions 187 and 188 which in turn rotate the larger pinions 190 and 191 respectively. As these larger pinions 190 and 191 mesh with the smaller pinion 192, which is rigidly secured to portion 67 of shaft 14, rotation of the shaft is accordingly achieved through this train of gears and, furthermore, due to the gear ratios of the successive pinions, the speed of shaft 14 is materially increased as compared to the speed achieved by the direct worm drive described above. The purpose and coaction of this faster speed with certain other features of the invention will be described more fully hereinafter. 135
- 80 Turning to Figures 1 and 2, it will now be clear that, when lever 209 is in the position shown in the drawings, so that plunger 204 is out of the path of movement of side plate 175 of housing 176, a slow speed (for purposes described hereinafter) of shaft 14 results when motor 56 (Figure 7) is operating. However, when a greater speed is required (for purposes described hereinafter), it is merely necessary to move lever 209 to the right into its other position in order to cause shaft 14 to be driven at a rapid speed in the manner described above. 140
- 85 In order to lubricate the various moving parts contained within casing 31, there is preferably provided an oil cup 217 or the like, as more clearly shown in Figure 3. Also, the casing 31, being closed entirely, one may, if desired, fill the casing with a suitable grease or like lubricant, and run the mechanism submerged in lubricant. The 145

various closures to the casing 31 may be gasketed if desired.

- Formed within and preferably integral with the top portion of frame 11, as is best seen in Figure 2, is a casing 68 within which is a worm 69 sleeved upon and rigidly secured to shaft 14. Worm 69 meshes with a worm wheel 70 rotatably mounted, as described below, and rotating within a suitable round opening 71 in frame 11.
- As is more clearly shown in Figure 1, there is provided an arm 72 preferably pivotally mounted upon a stud 36, or the like, extending from frame 11 to one side of opening 71. Worm wheel 70 is rotatably carried by arm 72 by way of a stud 73 carried by arm 72. The right hand end of arm 72 as viewed in Figure 1, lies within an L-shaped part 74, the lower end of which carries a vertically mounted screw 74a extending therethrough toward arm 72. Part 74 is connected to frame 11 by a pin 75 or the like eccentrically mounted in shaft 76. The latter is rotatably mounted in frame 11 and is manually rotatable by a handle 76a so that by rotation thereof a vertical movement of worm wheel 70 into or out of mesh with worm 69 may be achieved. Thus, by swinging the handle 76a to raise and lower the eccentric pin 75, the worm wheel 70 may be engaged with the worm 69 on the driven shaft 14 or disengaged therefrom, for a purpose to be described more clearly hereinafter.

The arm 72 engages the upper end of the adjusting screw 74a (Figure 1) so that the relation between arm 72 and the part 74 may be adjusted and the tightness with which the worm wheel 70 and the worm 69 are brought into mesh predetermined; the same adjustment may be utilized to take up wear of these gears or their teeth.

A connecting rod 77 is eccentrically pivoted to worm wheel 70 preferably by way of a stud bolt 37 and in turn pivotally connected to a vertical arm 78, as viewed in Figures 1 and 2, of a rack 79 which is slidably mounted in suitable bearings 79a and 79b in the frame 11. Rack 79 extends toward the right or to the front of the machine. When shaft 14 is rotated at either of the speeds above mentioned, worm wheel 70 rotates therewith, thus causing connecting rod 77 to impart a reciprocating movement to rack 79. Rigidly secured to shaft 73 is an arm 38 carrying a weight 38a, the weight of which is sufficient to insure rotation of worm wheel 70 when arm 77 is in a dead center position.

Turning back to Figure 2, there is shown an arm 80 integrally formed with and extending from frame 11 in a right hand direction, as viewed therein, upon which is preferably formed a vertically extending sleeve-like member 81. A shaft 82 is rotatably fitted within member 81 and carries upon its top portion a pinion 83 meshing with rack 79, as is more clearly shown in Figure 6. Accordingly, as reciprocating motion is imparted to rack 79, in the manner described above, oscillatory rotation is imparted to gear 83 and hence to shaft 82 and its connected parts, as will be more fully described hereinafter.

As is best shown in Figures 2 and 6, the upper end of the shaft 82 is provided with a longitudinally extending platform or table 82a in the upper face of which are formed ways 82b—82c in which is seated a plate-like arm 84. Preferably there is provided a slot 85 in arm 84 through which a screw 86 extends, this screw being threaded into table 82a. By means of bolt 86, the arm 84 is clamped to the table portion 82a while the

slot 85 permits the arm 84 to be adjustably positioned along the ways 82b—82c, for a purpose described hereinafter. To give a greater range of adjustment to the arm 84 lengthwise of the ways, one may and preferably provides in the table portion 82a another threaded hole 87 into which one may engage and thread the clamping screw 86 and thus give the slot 85 a different range of adjustment to the arm 84. As the rack 79 is thus reciprocated, shaft 82 is given an oscillatory rotary motion and arm 84 is swung back and forth through an arc substantially 180°, or more or less, having its center at the axis of the shaft 82. As appears clearly from Figures 1 and 2, this center or axis of the arc of swing of the arm 84 is underneath the rotating hat block 15 and somewhat near or to the left of its longitudinal center point.

The weight of shaft 82 and the parts carried thereby is carried by the upper end of the sleeve-like bearing 81 (Figure 2) against which the pinion or gear portion 83 rests, these parts being preferably provided with substantial areas of bearing surface. The lower end of shaft 82 which, to achieve greater lightness, may be hollow as shown in Figure 2, is exteriorly threaded to receive a nut 82d, locked by a lock nut 82e, thus to hold the shaft 82 and its related parts in proper assembled relation to the bearing 81.

Mounted upon arm 84, in a manner to be described hereinafter, is a hat finishing tool 88 which preferably takes the form of an electrically heated iron. Tool 88 is in engagement with the hat on the block 15 and when pressed against hat 35, in a manner to be presently described, and 110 when shaft 14 is rotating to rotate block 15 with hat 35 and impart motion to arm 84, moving in the above-described arc, the swinging tool 88 traverses the crown of the rotating hat. As is often the case it may be necessary to iron or lure 115 hats of different sizes and shapes and in order that tool 88 may be made to pass about such hats in a dependable manner it is merely necessary to loosen bolt 86 and move arm 84 to the length best suited to the particular size or shape of the 120 hat being ironed.

Still referring to Figure 2, the right hand end of arm 84 has formed thereupon a portion 89 bored out in a direction crosswise of arm 84 and carrying upon its top side a series of ratchet teeth 90. As is more clearly shown in Figure 11, a stud shaft 91 extends through the bore of portion 89 and is rigidly held therein against rotation by a set screw 92 extending through portion 89 (Figure 2). Fitted about portion 89 is a casing 94 (Figures 10 and 11), one side wing 94a of which extends downwardly, as viewed in Figure 11, and has the shaft 91 passed therethrough. An intermediate wing 94b of the housing 94 (Figures 10 and 11) extends downwardly along 135 the other side of the portion 89 and likewise has the shaft 91 passed therethrough, thence the casing 94 is extended to the right, as viewed in Figures 10 and 11, and is given a substantially cylindrical shape as at 94c (Figure 13), its outermost side wall 94d (Figures 10 and 11) being also apertured to receive the right hand end of the shaft 91. This cylindrical housing portion of the casing 94 houses a coiled or spiral spring 106, in a manner described in detail hereinafter, 140 spring 106 acting to tend to swing the housing 94, and parts carried thereby, in counter-clockwise direction about the axis of stud shaft 91, as viewed in Figures 2 and 13.

The outermost side wall 94d of the casing 94 150

is made detachable in any suitable way to permit the mounting of the spring 106.

The part 94, thus adapted to pivot about the shaft 91 (see Figures 2, 10, 11 and 13), has formed thereon an upwardly directed boss 112 which is bored out to receive a stud shaft 116 (Figures 2 and 11) and, as appears clearly in Figure 2, the part 94 has an integrally formed bracket 96 extending toward the right and bored out to receive the lower end of a tubular member 97 which is rigidly secured in place in any suitable manner.

At its upper end, the tubular support 97 extends through a suitable aperture in the member 98 which is rigidly secured thereto in any suitable way, member 98 extending to the left (Figures 2 and 1) into substantial parallelism with the lower bracket-like extension 96 of the housing part 94. The left hand end of arm 98 is bored out as at 113, this bore being coaxial with the bore in the lower boss 112.

In the bore 113 is received a tubular trunnion 115 of a generally rectangular shaped yoke 114 (see Figure 11) whose lower end is turned to provide the trunnion 116 that is rotatably fitted in the bore of the boss 112 which thus forms a counterpart to the trunnion 115. The yoke 114 is thus capable of freely oscillating about the vertical axis of the trunnions 115 and 116.

The horizontally spaced side members 114a and 114b (Figure 11) of the yoke 114 are shaped to provide half-bearings in which rests a cross stud shaft 129 that is rigidly held in place by counterpart of the bearing members 114c (see Figure 1) that are held by screws 114d to securely clamp stud shaft 114 in place.

The ironing tool 88 (Figure 2) is provided with a heavy lug or extension 133 through a suitable bore of which the shaft 129 extends, the tool-lug or extension 133 being received between and held against movement along the shaft 129 by lugs 131 and 132 (Figure 1) formed integrally with the frame 114 and through suitable bores in which the shaft 129 passes.

By this construction, therefore, the tool 88 may relatively freely pivot, throughout a limited extent, about the horizontal axis provided by the shaft 129 (Figures 2 and 11) and may also pivot about the vertical axis of the trunnions 115—116, all while being traversed throughout the arc of travel of the supporting arm 84 as the latter swings back and forth about the axis of the shaft 82 (Figure 2). The purpose of this mounting of the iron in the frame formed by the parts 96—97—98 (Figure 2) will be more clearly described hereinafter. The conductors 134—135 that lead the current to the iron 88, may conveniently be passed upwardly through the frame-tube 97 and thence through a flexible metal conduit 136 (Figure 2) one of whose ends extends and is secured in the upper end of the tube 97 and the other of whose ends passes through and is secured to the hollow trunnion 115. Thus, the cable or conductors are nicely held in a position where they cannot become entangled as the tool traverses the hat.

During this traversing motion back and forth of the iron 88, throughout the arc of which the axis of shaft 82 (Figure 2) is the center, the iron 88 is pressed against the hat on the block 15 by the action of the spring 106 (Figures 11 and 13). As above noted, spring 106 is within the cylindrical portion of the housing 94; it is made of suitable heavy flat spring steel stock and its one end 107 is received within a slot 108 that extends axially along that portion of the shaft 91 that is

within the spring housing; its other and outer end is bent into the shape of a hook 109 (Figure 13) which may be hooked into any one of several slots 110 provided in the cylindrical wall of the spring housing 94c. The left hand end of shaft 91 (Figures 10 and 11) is squared off as at 91a to receive a wrench or the like so that, after the set screw 92 has been suitably loosened up to free the shaft 91, shaft 91 may be manually rotated by the wrench or other suitable tool, thus appropriately or suitably to wind up or tension the spring 106, whereupon the set screw 92 is driven home and the shaft 91 locked against rotation, the spring 106 remaining tensioned. A wide range of tensioning may thus be given the spring 106 and this range may be further varied or increased by shifting the hook 109 (Figure 13) to any desired slot 110.

The tensioned spring 106 tends to swing the housing 94 and hence the frame and the iron 88 carried thereby in counter-clockwise direction, as viewed in Figures 1 and 2, and hence virtually determines the pressure with which the iron 88 engages the hat 35. This pressure may have to be varied from time to time depending upon various factors such as the quality of the fur felt hat body operated upon, the speed of rotation of the hat body, and other factors, and, by the construction above described, a wide range of different practical conditions may be quickly 105 and dependably met.

Turning now to Figure 11, it will be noted that the lower part of yoke or frame 114 is provided with a portion 121 immediately above the trunnion 116; fitted about this portion 121 and 110 rigidly connected thereto is a cross-arm 119 (Figures 12 and 10), member 119 partaking of whatever oscillation about a vertical axis that frame 114 and hence the iron 88 is subjected to. The ends of the cross-arm 119 (Figure 12) are apertured so as to receive the reduced end portions of a substantially U-shaped or semi-circular yoke 117, the latter being held rigidly connected to the part 119 by nuts 120 threaded onto the reduced ends of the member 117. The member 120 117 has the curvature of the part of a circle and is mounted to be concentric with the axis of the trunnions 115 and 116; it passes through a ring 123 that is integrally formed with a sleeve-like member 118 that is carried by the vertical frame-tube 97 (Figure 2) to which it is rigidly secured as by a pin, as is indicated in Figure 1. As the yoke 114 thus swings about its vertical axis, the member 117 (Figure 12) moves through the relatively stationary ring 123.

Near its ends, the member 117 carries collars 124 and 127 (Figure 12), the position of which along the member 117 may be determined and changed at will by sliding these collars along the part 117 and locking them in their selected 135 position as by the thumb screws 125 and 128.

Interposed between the collar 127 (Figure 12) and the ring 123 and extending about the member 117 is a helical spring 126 and, interposed between the other collar 124 and the ring 123, 140 is a similar spring 122. The springs 126 and 122, reacting against the fixed ring 123 and upon the adjustable collars 127 and 124 respectively, yieldingly hold the flat face of the ironing tool 88 substantially at right angles to the longitudinal axis of the swinging arm 84 but permit a yielding swinging of the frame or yoke 114 about the axis of the trunnions of the latter.

As the hat 35 is rotated and the iron 88 made to traverse the hat crown throughout a range 150

- of about 180°, the spiral spring 106 (Figures 11 and 13) holds iron 88 in contact with the hat at the desired pressure. While the universal mounting of the iron permits the latter to set 5 itself automatically and always tangentially to the curved surface of the hat itself, this action being aided by the springs 122 and 126 (Figure 12) which aid in achieving the proper tangential relation of the iron to the hat, particularly as 10 the latter moves from the side portions of the crown to the top of the crown or vice versa. The region that joins the side or band portion of the crown with the tip or apex of the crown of the hat is called the "square" of the hat and 15 its curvature may vary widely according to the style or shape of the crown operated upon. If this "square" is of long radius of curvature, the flat faced iron 88 has relatively little difficulty in making the traverse but, as the sharpness of 20 the curvature of this square increases, the difficulties confronting the iron 88 increase; it is in this latter connection particularly that the springs 122 and 126 come into action in that they insure the maintenance of the tangential 25 relation as the iron proceeds across the "square" of the hat and prevent the iron from suddenly flopping from the tip to the band portion of the hat or vice versa. The action of the springs may be varied to meet the particular conditions 30 met with in practice by appropriately setting the adjustable collars 124 and 127 (Figure 12), by which action the expansive forces of the springs are increased and, correspondingly, the yieldability of the swinging of the iron about the 35 axis of the trunnions of frame 114 diminished. The above-mentioned peculiar actions are accentuated where the hat is of oval cross-section as is indicated in Figure 14 and, in that case, the pivoting of the iron 88 about the horizontal axis 40 of the shaft 129 (Figures 2 and 11) coacts to maintain the desired tangency at all times, the spring 106 (Figure 13) insuring the maintenance of good contact between the iron and the hat 45 block and permitting the former to move toward and away from the axis of rotation of the oval shaped hat.
- Certain other coactions between the various parts of the apparatus thus far described will be dealt with in detail hereinafter.
- 50 When it is desired to remove the hat block, the iron 88 is swung away from the latter and is swung in clockwise direction, as viewed in Figures 1 and 2; more particularly, the operator grasps the handle 99, which is preferably integrally formed with the bracket arm 98 (see Figure 2), and swings the frame 98—97—96—94 in clockwise direction about the axis of the shaft 91 (Figures 10 and 11), the wings 94a, 94b and 94d of the casing 94 (Figure 11) permitting this 55 action to take place.
- During this swinging action, the pawl 103 (Figure 2), pivoted on a pin 101 held by a downwardly directed lug within the housing 94 (see Figures 10 and 11), rides over the ratchet teeth 60 90, being spring-urged into engagement with the ratchet teeth 90 by the spring 104 (Figure 2) that is housed within the upper part of the handle 99 and which acts against the thumb knob or button 105 that projects from the handle 99 and 65 which is connected to a rod 100 that extends downwardly where it is pivotally connected to the right hand end of the pawl 103. Rod 100 is guided in its sliding movement by the bore 99a 70 extending lengthwise through the handle 99 and 75

by a bore 96a provided in the bracket 96 that holds the lower end of the tubular support 97.

The pawl 103 thus comes into engagement with one of the ratchet teeth 90, depending upon the extent to which the handle 99 with its associated parts is swung about the axis of the shaft 91, automatically, under the action of spring 104, seating itself against a tooth and thus holding the iron 88 and related parts away from the hat block. 80

If desired, the above operation may be accompanied by a stoppage of the swinging traversing movement of the iron 88 in which case the handle 76a (Figure 1) is swung so as to disengage the worm wheel 70 from the worm 69, whereupon the reciprocation of the rack 79 stops and the swinging movement of arm 84 ceases. 90

The chuck which holds the hat block 15 may then be actuated either by hand, as by swinging the lever 28 (Figures 1 and 2) in clockwise direction, or by the foot, by stepping upon the foot treadle 34 (Figure 1), thus to move the chuck controlling collar 22 (Figure 2) to the left to cause the springs 21 to move the gripping fingers 18 out of engagement with the hat block. With 100 the hat block 15 thus released, the latter may be removed and replaced with another hat block on which has been mounted a hat. However, as will be pointed out hereinafter, means is provided also for removing the hat 35 itself without removing the block 15 from the chuck. 105

To bring the iron 88 back into operative contact with the hat 35, the operator presses the control knob 105 (Figure 2) at the upper end of handle 99, thus lifting the pawl 103 out of engagement 110 with the ratchet teeth, whereupon the spring 106 (Figures 11 and 13) swings the iron-supporting frame in counter-clockwise direction, as viewed in Figures 1 and 2, about the axis of shaft 91 and into engagement with the already rotating hat, 115 whereupon the actions above-described are repeated.

If the hat being operated upon is an oval shaped hat, the speed of rotation of the hat must be appropriately apportioned or selected for, if the oval shaped hat rotates too rapidly, damage to the hat is liable to occur and great irregularity and non-uniformity of ironing achieved; certain aspects of these actions will be clear by reference to Figure 14 in which an oval shaped hat 35a 125 is shown as it would appear when viewed from the right in Figures 1 and 2, but with the iron 88 in engagement with the side or band portion of the crown. If the speed is too great, substantially only the leading parts of those portions of the hat along the major axis of the oval would strike the iron 88 while the receding parts of those portions as well as the portions adjacent the minor axis of the oval would hardly be touched, if at all. Accordingly, when ironing an oval shaped hat, one shifts the control lever 209 (Figures 1 and 2) into the position shown in Figures 2 and 3, in which the control plunger 204 is withdrawn and is out of the path of movement of the lever arm 200 of the pawl 197 (Figures 9, 140 4 and 5). The driving parts are then in the positions shown in Figures 4 and 5, and the drive from the motor 56 (Figure 7) to the shaft 14 proceeds by way of the worm 149 (Figures 3 and 4), worm wheel 146, driving sleeve 145 (Figure 3) of 145 the latter and from the latter directly to pinion 192, the intermediate pinions and the auxiliary inner housing 176 (Figures 4 and 5) rotating as a unit. This speed of drive is such that the shaft 14 and hence the oval shaped hat on the block 15 150

(Figures 1 and 2) are rotated at a speed of about 40 or 50 R. P. M.

At this speed the above-described detrimental actions, mentioned in connection with Figure 14, cannot take place and the iron 88, mounted and acting as above-described in detail, is made nicely and dependently to follow the varying contours and varying lengths of radii of the hat body faithfully, achieving uniform ironing action without damage to the hat.

As the oval shaped hat body rotates and, particularly while the iron 88 is acting upon the oval portions thereof, for example, as is indicated in Figure 14, the pressure of the iron 88, caused by the spring 106 (Figures 11 and 13), acts alternately to oppose the rotation of the hat and to aid its rotation, depending upon whether the oval shaped hat body is forcing the iron 88 away from the axis of the hat or is causing the iron 88, under the urge of the spring 106, to move inwardly toward the axis of the hat and thus follow up the shortening radii of the latter.

This action causes peculiar reactions upon the drive of the shaft 14, in effect, causing the torque necessary to rotate it to vary throughout relatively wide ranges for each revolution of the hat. These reactions are reflected in the driving gearing interposed between the left hand end of the shaft 14 and the motor 56 and results in a pronounced tendency to oscillate the casing 31 (Figures 7 and 8) with the motor 56 carried thereby about the axis of the shaft 14. It is in this connection, also, that the cantilever stud 45 (Figures 2 and 3) and the arm 43 extending downwardly from the housing 31 come into play.

The cantilever stud 45, as above pointed out, is rigid and has great resistance to bending and the same is true of the depending arm 43; these tendencies to oscillate the housing 31 are transmitted by the arm 43 to the cantilever stud 45 which dependably negatives these tendencies and rigidly anchors and holds the casing 31 against such oscillation. Moreover, the widely varying and rapidly repeated torque that is thus imposed upon the housing 31 and which might otherwise easily loosen the housing 31, is dependably negated by this cantilever construction whose connection to the housing, through the relatively long arm 43 (Figure 2), has a relatively long lever arm for resisting these torsional or twisting effects.

If the hat operated upon is of circular cross-section, as is indicated in Figure 15, the iron 88 maintains a substantially constant and relatively invariable distance from the axis of rotation of the round hat 35b of Figure 15 and the above-described reactions are substantially eliminated as is also the requirement for a correspondingly low rate of drive of the hat as is forced upon the apparatus if the hat is oval shaped, as is the hat 35a of Figure 14. In this case, therefore, means is provided for saving in time and for increasing the rate of production in that one is enabled, in accordance with certain features of the invention, to rotate the round hat 35b at a greater rate of speed and correspondingly to traverse the iron 88 more rapidly about the hat.

Therefore, one shifts the control handle 209 (Figures 1 and 2) to the right, thus to move the control plunger 204 (Figures 2 and 3) to the left and cause it to effect disengagement of the pawl 197 (Figures 4 and 5) from the pinion 192 and to prevent rotation of the inner housing 176; the drive of shaft 14 and hence of the round hat

then proceeds by a new chain of mechanism, already above-outlined, but which it may again be pointed out, proceeds from worm 149 (Figures 7 and 4), worm wheel 146, driving sleeve 145 (Figure 3), pinion 189 which drives the smaller pinions 188 and 187, with which are coaxially mounted and by which are driven the larger pinions 191 and 190 respectively, the latter driving the smaller pinion 192 on the portion 67 (Figure 3) of the main shaft 14, the ratio of these various gears being such that the shaft 14 is now driven at a higher speed than before, illustratively at a speed on the order of 100 R. P. M.

Not only is the round hat rotated at a higher speed, but the reciprocations of the rack 79 (Figures 2 and 6) take place at a higher rate and the iron 88 is made to traverse the hat faster than it traverses the oval shaped hat.

Thus, one is enabled efficiently and dependably to meet the varying requirements met with in practice and to quickly condition the apparatus for operation upon the different shapes and kinds of hat bodies met with in practice. Also, it will be seen that one is enabled greatly to speed up production without impairment of uniformity and high quality of result.

As above pointed out, successive hat bodies may be operated upon by mounting the hat body on an appropriate hat block while the apparatus is itself operating upon another hat on another hat block; in such cases the block-chuck is operated to replace block and hat as a unit. In accordance with certain other features of the invention, however, it is possible to achieve a rapid and dependable mounting of the hat upon the block it- self without removing the latter from the apparatus, such procedure being in practice sometimes necessitated by various practical conditions.

In such case, one leaves the hat block 15 securely gripped in the chuck and, after swinging the iron 88 out of operative contact with the hat, the control lever 209 is moved to the left and into the position shown in Figure 2 in which, as appears clearly from Figures 4 and 5, the pivoted pawl 197 is released and placed under the action of its spring 202. The rotation of the hat block is then halted as by operating the main switch 218 (Figure 1) which is included in the circuit of the driving motor 56 (Figure 7). If at this time it is desired to swing iron 88 and its frame 120 to one side of the hat block, one operates the lever 76a (Figure 1) to disengage the worm wheel 70, whereupon one may manually swing the iron with its frame and supporting arm 84 about the axis of the shaft 82 (Figure 2) to a position to 125 the right or left of the hat block, thus making the latter with its hat freely and unobstructedly accessible to the operator.

The hat may then be stripped off of the hat block 15 and, in the course of this operation, the operator may freely rotate the hat block and the shaft 14 in one direction, the pawl 197 (see Figure 4) permitting such one-directional rotation freely to take place. The operator is thus enabled evenly and uniformly to apply the necessary forces to the hat to take it off of the block 15.

The next hat body is then ready to be pulled or stretched onto the hat block and, during this operation, uniform tensioning of the hat about its periphery should be exerted to stretch it over the block; here again the freedom or rotation of the shaft 14 and the block 15 permitted by the pawl 197 (Figure 4), are of great advantage.

But the pawl 197 acts, as has already been made clear, to permit rotation in only one direc-

150

tion and hence to prevent rotation in the other direction. This is an important practical feature since, in pulling the hat onto the hat block 15, the operator cannot achieve speed and uniform action if the hat block is free to rotate in either direction. But with my apparatus, the operator may, at any moment that is necessary during the operation of stretching a hat onto the block, direct his forces so as to tend to rotate 10 the hat block and the shaft in such a direction that the pawl 197 halts both shaft and block and the operator is thus enabled to obtain the necessary purchase on the hat body and direct his forces against a fixed hat block and, by rotating 15 the hat block in successive steps in the direction in which it is permitted to rotate by the pawl 197, he can at any point in the periphery of the hat achieve the fixed relation of the block and the opposition to his applied forces that are necessary, all under the operator's control and simply by exerting at will and as the need arises, such forces as are necessary and in the rotational direction as desired. Thus, rapid and efficient 20 mounting of the hat on the hat block, as well as dismounting thereof, may be reliably achieved.

Sometimes, the forces necessary to apply the hat to the hat block are substantial and where they are applied in a direction to tend to rotate the shaft 14 against the holding action of the 25 pawl 197 (Figure 4), correspondingly substantial forces are exerted upon the casing 31 (Figure 2) in a direction tending to rotate the casing about the axis of the shaft 14; here again, however, the cantilever mounting 43-45 (Figure 2) resists these forces and achieves a reliable and dependable anchorage, in coaction with the pawl 197, of the shaft 14 against rotation. Moreover, this cantilever mounting makes it possible for me to utilize, in the parts related thereto, constructions 30 that are light in weight as well as compact.

Recurring to Figure 1, it will be noted that the cable 137 that leads the conductors 134-135 (Figure 2) to the iron 88, leads to a rheostat 138 mounted on a side of the pedestal or frame support 10 and, by means of this rheostat, one may regulate or adjust the temperature at which the iron 88 operates.

It will thus be seen that there has been provided in this invention an apparatus in which the various objects hereinabove set forth together with many thoroughly practical advantages are successfully achieved. It will be seen that the apparatus is of a rugged construction and dependably uniform and efficient action throughout, and that it is well adapted to meet the varying requirements for practical use. For example, in this latter connection, it might be pointed out that, aside from the important coactions of the speed change mechanism with the shape of the hat operated upon, one may also utilize the achievement of the higher rate of drive of the hat block for such other operations as luring, in the course of which, the luring pad is held by hand against the rotating hat body and, in the course of which operation, a higher speed, even on an oval shaped hat, may be utilized without any danger of harm coming to the hat itself.

This application is a continuation in part of application Serial No. 164,393, filed January 29, 1927 patented January 12, 1932, Patent No. 1,841,345.

As many possible embodiments may be made of the above invention and as many changes might be made in the embodiment above set forth, it is to be understood that all matter here-

inbefore set forth or shown in the accompanying drawings is to be interpreted as illustrative and not in a limiting sense.

What is claimed is:

1. In apparatus of the character described, in combination, means adapted to support and rotate a hat, a tool for operating on the hat, a movable support, said tool being spring-supported by said support and urged by the spring against said support, means for moving said support to cause the tool to traverse the hat, a handle for manually moving said tool, a latch adapted to hold said tool away from said hat support in opposition to said spring, and means associated with said handle for controlling said latch. 8
2. In apparatus of the character described, in combination, means adapted to support and rotate a hat, a tool for operating on the hat, a movable support, a frame pivoted to said support about an axis such that said frame may move 9 toward or away from said hat support, said frame supporting said tool, and a spiral tensioned spring coaxial with the axis about which said frame pivots for yieldingly urging said frame about its pivot, the pivotal connection between said frame 10 and said support including a shaft rigidly connected to one of its related parts, one end of said spring being anchored to said shaft, and means adapted to permit rotation of said shaft and to lock it in place to determine the tension of said 10 spring. 10
3. In apparatus of the character described, in combination, means adapted to support and rotate a hat, a tool for operating on the hat, a frame, an auxiliary frame carrying said tool and 11 pivotally supported in said first frame, means for moving said first frame in a path to cause the tool to traverse the hat on said support, an arcuate member carried by said auxiliary frame and supported by said first-mentioned frame coaxial- 11 with the axis of said auxiliary frame, means fixed to said first frame adjacent said arcuate member, and a pair of springs on said arcuate member, one on each side of said last-mentioned means. 120
4. In apparatus of the character described, in combination, means adapted to support and rotate a hat, a tool for operating on the hat, a frame, an auxiliary frame carrying said tool and pivotally supported in said first frame, means for 125 moving said first frame in a path to cause the tool to traverse the hat on said support, an arcuate member carried by said auxiliary frame and supported by said first-mentioned frame coaxially with the axis of said auxiliary frame, 130 means fixed to said first frame adjacent said arcuate member, a pair of springs on said arcuate member, one on each side of said last-mentioned means, and means for setting the tension of said springs. 135
5. In a hat ironing machine, in combination, a frame having a horizontal shaft, said shaft having a chuck at one end thereof for supporting a hat block, an ironing tool, means for causing said ironing tool to traverse the crown of a hat on said 140 hat block as the latter is rotated, said iron being yieldably urged toward said hat block, a casing fitted to said frame adjacent the other end of said shaft, said frame and casing having interfitting parts coaxial with the axis of said shaft, an 145 electric motor carried by said casing, speed change mechanism within said casing and interposed between said motor and said shaft, said casing having a cantilever arm extending therefrom and along said frame, and a cantilever stud project- 150

- ing from said frame and rigidly connected with said arm for holding said casing against rotation about the axis of said shaft.
6. In a hat ironing machine, in combination, a frame having a horizontal shaft, said shaft having a chuck at one end thereof for supporting a hat block, an ironing tool, means for causing said ironing tool to traverse the crown of a hat on said hat block as the latter is rotated, said iron being yieldably urged toward said hat block, a casing fitted to said frame adjacent the other end of said shaft, said frame and casing having interfitting parts coaxial with the axis of said shaft, an electric motor carried by said casing, speed change mechanism within said casing and interposed between said motor and said shaft, and means including a cantilever stud projecting from said frame for holding said casing to said frame.
- 20 7. In a hat ironing machine, in combination, a frame having a horizontal shaft, said shaft having a chuck at one end thereof for supporting a hat block, an ironing tool, means for causing said ironing tool to traverse the crown of a hat on said hat block as the latter is rotated, said iron being yieldably urged toward said hat block, a casing fitted to said frame adjacent the other end of said shaft, said frame and casing having interfitting parts coaxial with the axis of said shaft, an electric motor, speed reduction gearing within said casing having one member driven by said motor and having another member driving said shaft, and means including a cantilever stud holding said casing to said frame and against rotation relative to the latter and against axial movement away from said frame.
- 25 8. In a hat ironing machine, in combination, a frame having a shaft journaled therein, a chuck at one end of said shaft for holding a hat block, an iron, means for yieldably urging said iron against a hat on said block and for causing the iron to traverse the crown of a hat as said block is rotated, a casing, said casing and said frame having concentric interfitting parts coaxial with said shaft, a source of motive power, speed reduction gearing within said casing for driving said shaft from said source of motive power, and means for preventing the cyclic thrust of said yieldingly urged iron against an oval shaped hat block from rotating said casing, said means including a cantilever arm extending from said casing and a cantilever arm extending from said frame and substantially at right angles to said first-mentioned cantilever arm and rigidly interconnected therewith.
- 40 9. In a hat ironing machine, in combination, a frame having a shaft journaled therein, a chuck at one end of said shaft for holding a hat block, an iron, means for yieldably urging said iron against a hat on said block and for causing the iron to traverse the crown of a hat as said block is rotated, a casing, said casing and said frame having concentric interfitting parts coaxial with said shaft, a source of motive power, speed reduction gearing within said casing for driving said shaft from said source of motive power, and means for preventing the cyclic thrust of said yieldingly urged iron against an oval shaped hat block from rotating said casing, said means including a cantilever stud projecting from said frame at a point spaced from the axis of said shaft and substantially parallel to the latter and engaging said casing.
- 45 10. In a hat ironing machine, in combination, a frame having a shaft journaled therein, a chuck at one end of said shaft for holding a hat block, an iron, means for yieldably urging said iron against a hat on said block and for causing the iron to traverse the crown of a hat as said block is rotated, a casing, said casing and said frame having concentric interfitting parts coaxial with said shaft, an electric motor carried by said casing, reduction gearing within said casing for driving said shaft from said motor, said gearing including a part adapted to rotate about the axis of said shaft, gear means rotatably mounted in said part, gear means mounted upon said shaft and coacting with said last-mentioned gear means, and means forming a driving connection between said motor and said first-mentioned gear means.
- 50 11. In a hat ironing machine, in combination, a frame having a shaft journaled therein, a chuck at one end of said shaft for holding a hat block, an iron, means for yieldably urging said iron against a hat on said block and for causing the iron to traverse the crown of a hat as said block is rotated, a casing, said casing and said frame having concentric interfitting parts coaxial with said shaft, an electric motor carried by said casing, reduction gearing within said casing for driving said shaft from said motor, said gearing including a part rotatably mounted upon said shaft, a plurality of pinions rotatably mounted in said part, a pinion fixedly secured to said shaft and meshing with said last-mentioned pinions, and means forming a driving connection between said motor and said plurality of pinions.
- 55 12. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions mounted in said housing member and meshing with said first-mentioned pinion, motive means, and means forming a driving connection between said motive means and said plurality of pinions.
- 60 13. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions mounted in said housing member and meshing with said first-mentioned pinion, an electric motor secured to said casing, and means forming a driving connection between said motor and said plurality of pinions.
- 65 14. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions mounted in said housing member and meshing with said first-mentioned pinion.
- 70 15. In a hat ironing machine, in combination, a frame having a shaft journaled therein, a chuck at one end of said shaft for holding a hat block, an iron, means for yieldably urging said iron against a hat on said block and for causing the iron to traverse the crown of a hat as said block is rotated, a casing, said casing and said frame having concentric interfitting parts coaxial with said shaft, an electric motor carried by said casing, reduction gearing within said casing for driving said shaft from said motor, said gearing including a part adapted to rotate about the axis of said shaft, gear means rotatably mounted in said part, gear means mounted upon said shaft and coacting with said last-mentioned gear means, and means forming a driving connection between said motor and said first-mentioned gear means.
- 75 16. In a hat ironing machine, in combination, a frame having a shaft journaled therein, a chuck at one end of said shaft for holding a hat block, an iron, means for yieldably urging said iron against a hat on said block and for causing the iron to traverse the crown of a hat as said block is rotated, a casing, said casing and said frame having concentric interfitting parts coaxial with said shaft, an electric motor carried by said casing, reduction gearing within said casing for driving said shaft from said motor, said gearing including a part rotatably mounted upon said shaft, a plurality of pinions rotatably mounted in said part, a pinion fixedly secured to said shaft and meshing with said last-mentioned pinions, and means forming a driving connection between said motor and said plurality of pinions.

in said housing member and meshing with said first-mentioned pinion, an electric motor secured to said casing, a gear member rotatably mounted upon said shaft, means forming a driving connection between said gear member and said motor, and means forming a driving connection between said gear member and said plurality of pinions.

15. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions rotatably mounted within said housing member, said pinions meshing with said first-mentioned pinion, a plurality of gear members mounted within said housing member and secured to said pinions, a sleeve member rotatably mounted upon said shaft, a pinion secured to said sleeve member and meshing with said plurality of gear members, an electric motor secured to said casing, a gear member secured to said sleeve member, a gear member secured to the shaft of said motor and meshing with said last-mentioned gear member whereby actuation of said motor imparts rotation to said housing member relative to said shaft and rotation to said shaft through said plurality of pinions and said first-mentioned pinion, and means for preventing relative rotation of said housing member and said shaft.

16. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions rotatably mounted within said housing member, said pinions meshing with said first-mentioned pinion, a plurality of gear members mounted within said housing member and secured to said pinions, a sleeve member rotatably mounted upon said shaft, a pinion secured to said sleeve member and meshing with said plurality of gear members, motive means, and means forming a driving connection between said motive means and said plurality of gear members whereby rotation is imparted to said housing member relative to said shaft and through said plurality of pinions to said shaft, and means for preventing relative movement between said housing member and said first-mentioned shaft.

17. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with

55 said shaft, said shaft extending into said casing, a pinion secured to said shaft within said casing, a housing member rotatably mounted upon said shaft within said casing, a plurality of pinions rotatably mounted within said housing member, said pinions meshing with said first-mentioned pinion, a plurality of gear members mounted within said housing member and secured to said pinions, a sleeve member rotatably mounted upon said shaft, a pinion secured to said sleeve member and meshing with said plurality of gear members, an electric motor secured to said casing, and means forming a driving connection between said electric motor and said sleeve member.

18. In apparatus of the character described,

in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions rotatably mounted within said housing member, said pinions meshing with said first-mentioned pinion, a plurality of gear members mounted within said housing member and secured to said pinions, a sleeve member rotatably mounted upon said shaft, a pinion secured to said sleeve member and meshing with said plurality of gear members, an electric motor secured to said casing, a gear member secured to said sleeve member, a gear member secured to the shaft of said motor and meshing with said last-mentioned gear member whereby actuation of said motor imparts rotation to said housing member relative to said shaft and rotation to said shaft through said plurality of pinions and said first-mentioned pinion, and means for preventing relative rotation of said housing member and said shaft.

19. In apparatus of the character described, in combination, a frame, a shaft rotatably mounted within said frame, a hat block affixed to said shaft and adapted to receive a hat, a tool for operating upon the hat on said block, a driving mechanism for said shaft including a casing secured to said frame and coaxial with said shaft, said shaft extending into said casing, a pinion secured to said shaft within said casing, a housing member rotatably mounted upon said shaft within said casing, a plurality of pinions rotatably mounted within said housing member and meshing with said pinion, a plurality of gear members rotatably mounted within said housing member and each secured to one of said plurality of pinions, a sleeve member mounted upon said shaft, a gear element affixed to said sleeve member and meshing with said gear members, a motor secured to said casing, gear members forming a driving connection between said motor and said sleeve member whereby upon actuation of said motor an indirect driving connection is formed between said gear element and said shaft including said rotatable housing member with the first-mentioned gear members and pinions carried thereby, and a stop member mounted on said housing member and adapted to jam with said first-mentioned pinion to prevent relative movement between said housing member and said shaft thereby to form a direct driving connection between said gear element and said shaft through said housing member.

20. In apparatus of the character described, in combination, a frame member, a shaft rotatably mounted in said frame member, a hat block secured to said shaft and adapted to carry a hat, supporting means pivotally mounted on an axis substantially at right angles to the axis of said shaft, means for imparting oscillatory motion to said supporting means about its axis, a frame member pivotally connected to said supporting means about a horizontal axis substantially at right angles to the axis of said supporting means and the axis of said shaft, an iron pivotally mounted in said last-mentioned frame member about an axis substantially parallel with the axis

- of said supporting means, said iron being substantially adjacent said hat block, spring means associated with said last-mentioned frame member and adapted to yieldably support said iron in 5 a plane substantially perpendicular to the radius through said first-mentioned axis, and spring means associated with said last-mentioned frame member and said supporting means and adapted to urge said last-mentioned frame member about 10 its pivotal point toward said hat block.
21. In apparatus of the character described, in combination, a frame, a horizontal shaft rotatably mounted in said frame, a hat block secured to said shaft, a supporting member pivotally mounted in said frame about an axis substantially vertical with respect to said shaft, a shaft 15 on said supporting member, a frame pivoted to said shaft and having a housing movable with said frame about the axis of said shaft, an ironing tool secured to said last-mentioned frame and substantially adjacent said hat block, and a spring within said housing and secured to said last-mentioned shaft and acting through said housing upon said last-mentioned frame and 20 adapted to urge said last-mentioned frame toward said hat block continuously.
22. In apparatus of the character described, in combination, a frame, a shaft rotatably mounted within said frame, means for affixing a hat block 25 to one end of said shaft, the end portion of said shaft opposite said last-mentioned means extending beyond said frame, a casing covering said end portion, an electric motor secured to said casing, means in said casing forming a driving 30 connection between said motor and said shaft, and means including a single cantilever stud adapted to hold said casing to said frame against rotation relative to said frame and against axial movement away from said frame.
- 40 23. In apparatus of the character described, in combination, a frame, a shaft rotatably mounted within said frame, means for affixing a hat block to one end of said shaft, the end portion of said shaft opposite said last-mentioned means extending beyond said frame, a cup-shaped casing covering said end portion, an electric motor secured to said casing, means in said casing forming a driving 45 connection between said motor and said shaft, and means for securing said casing to said frame including a cantilever arm extending from said casing and a cantilever stud extending from said frame substantially at right angles to said cantilever arm and rigidly interconnected therewith.
- 55 24. In apparatus of the character described, in combination, a frame, a shaft rotatably mounted within said frame, means for affixing a hat block to one end of said shaft, the end portion of said shaft opposite said last-mentioned means extending beyond said frame, a casing covering said end portion, an electric motor secured to said casing, means in said casing forming a driving 60 connection between said motor and said shaft, and means for securing said casing to said frame including an arm extending from the bottom side thereof substantially at right angles to the axis of said shaft to a point spaced below said shaft and secured to said frame substantially at said point.
- 70 25. In apparatus of the character described, in combination, a frame, a shaft rotatably mounted within said frame, means for affixing a hat block to one end of said shaft, the end portion of said shaft opposite said last-mentioned means extending beyond said frame, a casing covering 75
- said end portion, an electric motor secured to and extending away from said casing, means in said casing forming a driving connection between said motor and said shaft, and means for securing said casing to said frame and for taking up certain reactions of said motor on said casing including a cantilever stud projecting from said frame.
26. In apparatus of the character described, in combination, a frame, a shaft rotatably mounted within said frame, means for affixing a hat block to one end of said shaft, the end portion of said shaft opposite said last-mentioned means extending beyond said frame, a cup-shaped casing extending over said end portion, an electric motor, a portion of said casing fitting over a portion of said motor and secured thereto, means in said casing forming a driving connection between said motor and said shaft, and means securing said casing to said frame including a cantilever arm extending from said casing along said frame and a cantilever stud projecting from said frame and rigidly connected with said arm to prevent rotation of said casing about the axis of said shaft.
27. In apparatus of the character described, in combination, a frame, a shaft rotatably mounted within said frame, means for affixing a hat block to one end of said shaft, the end portion of said shaft opposite said last-mentioned means extending beyond said frame, a casing fitting over said exposed end portion, an electric motor, said casing having a cup-shaped portion fitting over one end of said electric motor, means securing said cup-shaped portion to said electric motor so that the axis of the shaft of said motor is substantially at right angles to the axis of said first-mentioned shaft, and means in said casing including a worm and worm wheel forming a driving connection between said motor and said shaft, a cantilever arm extending from the bottom of said casing in substantial alignment with said frame, and a cantilever stud projecting from said casing and rigidly secured to said arm at a point spaced from said first-mentioned shaft, said arm and said stud cooperating to secure said casing to said frame and prevent rotation of said casing about the axis of said first-mentioned shaft.
28. In apparatus of the character described, in combination, a frame, a shaft rotatably mounted within said frame, means for affixing a hat block to one end of said shaft, the end portion of said shaft opposite said last-mentioned means extending beyond said frame, a casing covering said exposed end portion and secured to said frame, a motor secured to said casing, a pinion secured to said shaft, means including a plurality of pinions forming a driving connection between said motor and said first-mentioned pinion for driving the latter at a certain speed, and means for forming a driving connection between said motor and said first-mentioned pinion for driving the latter at a different speed.
29. In apparatus of the character described, in combination, a frame, a shaft rotatably mounted within said frame, means for affixing a hat block to one end of said shaft, the end portion of said shaft opposite said last-mentioned means extending beyond said frame, a sleeve rotatably mounted upon said shaft, an electric motor, means forming a driving connection between said sleeve and said electric motor, a pinion secured to said shaft, means including a plurality of pinions forming a driving connection between said sleeve and said first-mentioned pinion, and means operable at will for forming a different

driving connection between said sleeve and said first-mentioned pinion and thereby changing the driving relation therebetween.

30. In apparatus of the character described, in combination, a frame, a shaft rotatably mounted within said frame, means for affixing a hat block to one end of said shaft, the end portion of said shaft opposite said last-mentioned means extending beyond said frame, means for supporting a motor in the vicinity of said exposed portion of said shaft, means including a worm gear rotatably mounted upon said shaft and forming a driving connection with the shaft driving element of said motor, a plurality of pinions mounted about said shaft and forming a speed reduction mechanism, means for connecting said pinions to said worm gear to form a driving connection between said motor and said shaft for driving the latter at a certain speed, and means for jamming said pinions to provide a driving connection between said worm gear and said shaft for driving the latter at a different speed.

31. In apparatus of the character described, in combination, a frame, a shaft rotatably mounted within said frame, means for affixing a hat block to one end of said shaft, the end portion of said shaft opposite said last-mentioned means extending beyond said frame, driving means rotatably mounted upon said shaft, motive means for driving said last-mentioned means, a pinion secured to said shaft, a housing member fitted about said shaft, a plurality of pinions mounted in said housing member and forming a speed reducing connection between said driving means and said first-mentioned pinion for driving the latter at a certain speed, and means operable at will for changing the operation of said second-mentioned pinions so that they form a different driving connection between said driving means and said first-mentioned pinion for driving the latter at a different speed.

32. In apparatus of the character described, in combination, a frame, a shaft rotatably mounted within said frame, means for affixing a hat block to one end of said shaft, a casing concentrically interfitting with the end of said frame opposite said last-mentioned means, a motor casing concentrically interfitting with said last-mentioned casing, means in said first-mentioned casing forming a driving connection between said motor and said shaft, and means for securing said first-mentioned casing to said frame including a cantilever stud projecting from said frame.

33. In apparatus of the character described, in combination, a frame, a shaft rotatably mounted within said frame, means for affixing a hat block to one end of said shaft, a casing a portion of which is concentric and interfits with the end of said frame opposite said last-mentioned means, a motor a portion of whose casing is concentric and interfits with said first-mentioned casing, the axis of the armature of said motor being substantially at right angles to the axis of said shaft, means in said first-mentioned casing forming a driving connection between said motor and said shaft, and means for securing said first-mentioned casing to said frame.

34. In apparatus of the character described, in combination, a frame, a shaft rotatably mounted within said frame, means for securing a hat block to one end of said shaft, an iron mounted on said frame, means for oscillating said iron about said block, a worm wheel mounted in said frame to rotate on an axis at right angles to the axis of the shaft, said shaft having a worm portion meshing with said worm wheel, means forming a driving connection between said worm wheel and said oscillating means, a casing secured to the end of said frame opposite said block and in registry with said shaft, a motor whose casing is secured to said last-mentioned casing, means in said first-mentioned casing forming a driving connection between said motor and said shaft, and means including a cantilever stud extending from said frame for connecting said first-mentioned casing to said frame.

35. In apparatus of the character described, in combination, a frame, a shaft rotatably mounted within said frame, means for securing a hat block to one end of said shaft, an iron mounted on said frame, means for oscillating said iron about said block, a worm wheel mounted in said frame to rotate on an axis at right angles to the axis of the shaft, said shaft having a worm portion meshing with said worm wheel, means forming a driving connection between said worm wheel and said oscillating means, a casing, a portion of which is concentric and interfits with the end of said frame opposite said block and in registry with one end of said shaft, a motor whose casing is connected to said first-mentioned casing and the axis of whose armature is at right angles to the axis of said shaft, means forming a driving connection between said motor and said shaft, and means connecting said first-mentioned casing to said frame.

36. In apparatus of the character described, in combination, a frame, a shaft rotatably mounted within said frame, means for securing a hat block to one end of said shaft, an iron mounted on said frame, means for oscillating said iron about said block, a worm wheel mounted in said frame to rotate on an axis at right angles to the axis of the shaft, said shaft having a worm portion meshing with said worm wheel, means forming a driving connection between said worm wheel and said oscillating means, a casing, a portion of which is concentric and interfits with the end of said frame opposite said block and in registry with one end of said shaft, a motor whose casing is connected to said first-mentioned casing and the axis of whose armature is at right angles to the axis of said shaft, means forming a driving connection between said motor and said shaft, and means for securing said first-mentioned casing to said frame including a cantilever arm extending from said casing and a cantilever stud extending from said frame and rigidly connected to said arm.

JOHN C. DORAN,
Executor of the Last Will and Testament of
James F. Doran, Deceased.
